UNITED STATES PATENT OFFICE.

WILLIAM C. MONOHON, OF FAIRBURY, NEBRASKA.

DESIGN FOR A LADY'S WORK-BOX.

SPECIFICATION forming part of Design No. 15,492, dated October 28, 1884.

Application filed June 11, 1884. Term of patent 3½ years.

To all whom it may concern:

Be it known that I, WILLIAM C. MONOHON, a citizen of the United States, and a resident of Fairbury, in the county of Jefferson and State of Nebraska, have invented a certain new and original Design for Ladies' Work-Boxes; and I do hereby declare that the following is a full, clear, and exact description of the invention, which will enable others skilled in the art to which it appertains to make and use the same, reference being had to the accompanying drawings, which form a part of this specification, and in which—

Figure 1 is a perspective view, and Fig. 2 is a side view, of a work-box showing my novel design.

Similar letters of reference indicate corresponding parts in both the figures.

My design has reference to ladies' work boxes or cabinets; and it consists in the ornamental features of the same, as will be more fully described and claimed.

In the accompanying drawings, A is a rectangular box provided with a top, B, and with an upper outwardly-projecting scalloped flange, C, and with a lower outwardly-projecting flange, D. Both flanges are developed at

the corners at E for the corner-posts F, which posts are formed into the inwardly-curved feet G at their lower ends. The vertical rods H 30 and the corner-posts are ornamented at their upper ends with caps J, shaped as the shell of an ordinary small-caliber rifle or pistol cartridge, or as a common percussion-cap.

Having thus described my design, I claim— 35

A design for a work box or cabinet comprising an oblong box having an upper scalloped and a lower straight flange, both flanges developed at the corners, four corner-posts having inwardly-curved feet at their lower ends 40 and ornamented with flanged caps at their upper ends, and the vertical rods ornamented at their upper ends with flanged caps, the said caps being shaped as the shell of a pistol or rifle cartridge, or as a common percussion-cap, 45 as shown and described.

In testimony that I claim the foregoing as my own I have hereunto affixed my signature in presence of two witnesses.

WILLIAM C. MONOHON.
